Attorney

UNITED STATES PATENT OFFICE.

JOHN J. THACHER, OF WETHERSFIELD, CONNECTICUT, ASSIGNOR TO PRATT & WHITNEY COMPANY, OF NEW YORK, N. Y., A CORPORATION OF NEW JERSEY.

DRILL-LUBRICATING PUMP.

Application filed May 5, 1921. Serial No. 467,057.

To all whom it may concern:

Be it known that I, JOHN J. THACHER, a citizen of the United States, residing at Wethersfield, in the county of Hartford and State of Connecticut, have invented certain new and useful Improvements in Drill-Lubricating Pumps, of which the following is a specification.

This invention relates to metal working machines and particularly to an improved means for supplying a lubricant to the tool or tools thereof.

The primary object of the invention is to provide a lubricating pump and improved means for operating the same in synchronism with the tooling operation whereby a lubricant is automatically supplied to the tools upon the relative approach of the tools and work.

More specifically it is an object of the invention to provide a lubricating pump in combination with a drilling machine and an operative connection between the pump and drill spindle whereby upon the feeding of the drill into the work the pump is automatically operated to supply a quantity of lubricant to the drill.

With the above and other objects in view, my invention consists in the features of construction and operation set forth in the following specification and illustrated in the accompanying drawing. In such drawing annexed hereto and forming a part of this specification, I have shown my invention as embodied in a center drilling machine but it will be understood that the invention can be otherwise embodied and that the drawing is not to be construed as defining or limiting the scope of the invention, the claims appended to this specification being relied upon for that purpose.

Referring to the figures of the drawing:

Figure 1 is a side elevation of a center drilling machine having my invention embodied therein.

Fig. 2 is a plan view thereof.

Fig. 3 is an enlarged cross sectional detail view taken on the line 3-3 of Fig. 2.

Fig. 4 is an enlarged detail view partially in longitudinal section.

In drilling and other metal cutting machines it is essential that the tools be properly supplied with a lubricant during the tooling operation, it being unnecessary, however, that such lubricant should flow continuously

over the tools while the same are inoperative. The present invention accordingly provides a lubricating pump in connection with a tool support or supports and synchronously operated therewith in a manner to cause a flow of lubricant over the tool or tools during the feeding movement thereof toward the work. In the drawing I have illustrated the pump piston as being positively connected to a drill spindle operating mechanism in a manner to operate the piston on a suction stroke during the rearward movement of the spindles and on a compression or oil feeding stroke during the forward or feeding movement of the spindles. The specific details illustrated in the drawing will now be described.

The bed of a center drilling machine is illustrated at 1 on which are mounted drill supporting heads 2 and 3, each head having a motor 4 mounted thereon for rotating the drill spindles. The head 3 is adapted to be adjusted along the ways 5 of the bed and to be clamped in adjusted position by means of a clamping handle 6. Longitudinally slidably mounted within each head is a drill spindle 7, each supporting a drill 8. Means comprising a rack 9 on each spindle and a pinion 10 is adapted to feed the spindles longitudinally. A handle 11 operatively connected to a shaft 12 supporting the pinion 10 in the head 2 is adapted to be operated to feed the spindle longitudinally. An arm 13 secured to the shaft 12 at the opposite side of the head is operatively connected by a link 14 to an arm 15 secured to a shaft on which is mounted a pinion 16 meshing with the pinion 10 in the head 3. By this means it will be seen that movement of the handle 11 in one direction is adapted to simultaneously feed both spindles forwardly and movement thereof in the opposite direction is adapted to feed the spindles rearwardly. 17 illustrates a pair of work supporting members adapted to support a piece of work W between the drill spindles 7. A hand clamp 17 pivoted on one of the members is adapted to assist in supporting small stock.

An oil reservoir 18 is provided beneath the bed 1 and a pump 19 is adapted to force oil therefrom through conduits 20 and 21 to the drills in the drill spindles. While I have illustrated the pump cylinder as formed integrally with the reservoir, it will

be readily understood that the same may be formed and positioned in any desirable manner. As illustrated in Figs. 3 and 4, the oil is adapted upon operation of the pump 6 to pass through a check valve 22 into the pump cylinder and thence through a check valve 23 into the conduits 20 and 21, the oil circulation being illustrated by arrows.

The pump piston 24 is operatively connected to the drill spindles through the mechanism heretofore described, including the link 14 connected to one end 25 of an arm 26 pivoted at 27 and having its other end connected to the piston rod 28. It will now be seen that movement of the handle 11 in a direction to move the spindles rearwardly will operate to move the piston outwardly to draw a charge of oil into the pump and movement thereof in the opposite direction will operate to move the piston inwardly to discharge oil therefrom through the conduits to the drills at the point of their engagement with the work. The link 14 is adjustably connected to the arm 15 at 15 whereby to permit the adjustment of the head 3 heretofore described. By means of such adjustment the machine may be set to operate on work of varying lengths.

What I claim:

1. In a machine tool, the combination of a tool support, means for supporting a piece of work, means for causing relative rotation between the tool and work, means for causing a relative feeding movement between the tool and work, a lubricating pump, an oil conduit leading from the pump to the tool, and pump operating means controlled by the relative feeding movement between the tool and work whereby upon relative approaching movement between the tool and work the pump will be operated to discharge a quantity of oil therefrom through the conduit to the tool.

2. In a machine tool, the combination of a tool support, means for supporting a piece of work, means for causing relative rotation between the tool and work, means for causing a relative feeding movement between the tool and work, a lubricating pump of the piston type, an oil conduit leading from the pump to the tool, and means for operating the pump piston synchronously with the tooling operation whereby upon relative approaching movement between the tool and work the pump piston will be moved in a direction to discharge oil from the pump through the conduit to the tool.

3. In a machine tool, the combination of a tool support, means for supporting a piece of work, means for causing relative rotation between the tool and work, means for causing a relative feeding movement between the tool and work, a lubricating pump of the piston type, an oil conduit leading from the pump to the tool, and means for operat-

ing the pump piston synchronously with the tooling operation whereby upon relative separating movement between the tool and work the pump piston will be moved in one direction to draw a charge of oil into the pump and upon relative approaching movement between the tool and work the pump piston will be moved in the opposite direction to discharge oil therefrom through the conduit to the tool.

4. In a drilling machine, the combination of a spindle, means for rotating the spindle, means for moving the spindle longitudinally toward and from a piece of work, a lubricating pump of the piston type, an oil conduit leading from the pump to the spindle, and means operatively connecting the spindle to the pump piston whereby on rearward movement of the spindle the piston will be moved in one direction to draw a charge of oil into the pump and upon forward movement of the spindle the piston will be moved in the opposite direction to discharge oil therefrom through the conduit to the spindle.

5. In a drilling machine, the combination of a spindle, means for rotating the spindle, means for moving the spindle longitudinally toward and from a piece of work, a lubricating pump of the piston type, an oil conduit leading from the pump to the spindle, and a positive operative connection between the spindle and the pump piston whereby rearward movement of the spindle operates to move the piston in one direction to draw a charge of oil into the pump and forward movement of the spindle operates to move the piston in the opposite direction to discharge oil therefrom through the conduit to the spindle.

6. In a drilling machine, the combination of a spindle, means for rotating the spindle, means for moving the spindle longitudinally toward and from a piece of work, a lubricating pump of the piston type, an oil conduit leading from the pump to the spindle, and an operative connection independent of the spindle between the spindle moving means and the pump piston whereby movement of the said means to move the spindle rearwardly operates to move the pump piston in one direction to draw a charge of oil into the pump and movement of such means in the opposite direction operates to move the piston in the opposite direction to discharge oil therefrom through the conduit to the spindle.

7. In a center drilling machine, the combination of a bed, a pair of drill supporting heads mounted thereon, one of such heads being longitudinally adjustable on the bed, a drill spindle slidably mounted in each head, means operatively connected to the spindles for simultaneously moving the same longitudinally toward and from a

piece of work supported between the spindles, a lubricating pump of the piston type, an oil conduit leading from the pump to each spindle, and an operative connection 6 between one of the spindles and the pump piston whereby upon rearward movement of the spindles, the pump piston will be moved in one direction to draw a charge of oil into the pump and upon forward movement of 10 the spindles the piston will be moved in the opposite direction to discharge oil therefrom through the conduits to the spindles.

8. In a center drilling machine, the combination of a bed, a pair of drill supporting 15 heads mounted thereon, one of such heads being longitudinally adjustable on the bed, a drill spindle slidably mounted in each head, means operatively connected to the spindles for simultaneously moving the 20 same longitudinally toward and from a piece of work supported between the spindles, a lubricating pump of the piston type, an oil conduit leading from the pump to each spindle, and an operative connection 25 between the spindle operating means and the pump piston whereby movement of such means in a direction to move the spindles rearwardly will operate to move the piston in one direction to draw a charge of oil

into the pump and movement thereof in the 30 opposite direction will operate to move the piston in the opposite direction to discharge oil therefrom through the conduits to the spindles.

9. In a center drilling machine, the combination of a bed, a pair of drill supporting heads mounted thereon, one of such heads being longitudinally adjustable on the bed, a drill spindle slidably mounted in each head, means for moving each spindle 35 longitudinally toward and from a piece of work supported between the spindles, a link connecting such means, a lubricating pump of the piston type, an oil conduit leading from the pump to each of the spindles, and 40 an operative connection comprising a pivoted arm between the link and the pump piston whereby movement of the link in a direction to move the spindles rearwardly will operate to move the piston in one direction to draw 45 a charge of oil into the pump and movement thereof in the opposite direction will operate to move the piston in the opposite direction to discharge oil therefrom through 50 the conduits to the spindles.

In testimony whereof, I hereto affix my signature.

JOHN J. THACHER.
